J. Franklin Meyer
ATTORNEY

UNITED STATES PATENT OFFICE.

JOHN H. CRONIN, OF LOUISVILLE, KENTUCKY, ASSIGNOR TO THE ENRO SHIRT COMPANY, OF LOUISVILLE, KENTUCKY, A CORPORATION OF KENTUCKY.

SHIRT AND SHIRT POCKET.

Application filed November 16, 1925. Serial No. 69,287.

The present invention is an improvement in shirts, especially of the sport type, and in methods of forming pockets therein.

In the usual construction of such shirts, wherein the opening is at the front, the closing flap is constituted in part by a formed tape or ribbon, usually of the same material, secured to the bosom of the shirt and provided with button-holes for receiving the buttons of the inner flap.

When the shirt is provided with a pocket or pockets, it is usually of the patch type and on the outer face of the shirt. Such pockets and the closing flap above mentioned are in relief on the shirt bosom and mar the smooth, uniform appearance of the same.

The subject matter of my prior application, Serial Number 735,810, filed on September 4, 1924, Patent No. 1,570,208, is a shirt wherein the closing flap forms a smooth, uninterrupted continuation of the front or bosom of the shirt, with the stitching hidden and with the free edge of the closing flap covered by a continuation of the shirt front, the intermediate plies of the flap being in rear of the bosom.

One of the primary objects of the present invention is to provide a pocket construction which with the exception of the pocket slit will be hidden by the shirt front, and will be connected to the shirt by stitching, all of which is in rear of the front and hidden thereby.

In the drawings:

Fig. 1 is a perspective view of the pocket with a part of the front wall broken away.

Fig. 2 is a similar view of a part of the shirt front, showing the outer face and the first step of the method.

Fig. 3 is a similar view of a part of the shirt front, showing the second step.

Fig. 4 is a section on the line 4—4 of Fig. 3. Figs. 5 and 6 are perspective views with parts broken away, showing successive steps and looking at the inner side or rear face of the shirt front.

Fig. 7 is a section on the line 7—7 of Fig. 9.

Fig. 8 is a rear view of the pocket, showing the final stage.

Fig. 9 is a similar view, looking at the front.

Fig. 10 is a front view, showing a flap for the pocket slit.

Fig. 11 is a section on the line 11—11 of Fig. 10.

In the present embodiment of the invention, the shirt is of the negligee or sport type and of any suitable or desired material. The front or bosom portion thereof, indicated at 1, is provided with a transverse or horizontal slit 2 at one side of the closing flap, not shown. The pocket, which is usually but not necessarily composed of the same material as the shirt body, consists of patches 3 and 4 similarly shaped, placed one upon the other, and secured together by a line of stitching 5.

The pocket is open at the top and the free top edges of the opposite walls are turned down upon the bodies of the walls in the same direction as indicated at 6 and 7, respectively. The turned-down portions or flanges are for the purpose of reinforcing the top edges of the pocket walls and to provide a finish. The portion or flange 6 of the rear wall is outside the pocket, while the flange 7 of the front wall is inside the pocket, that is, between the walls thereof, as clearly shown in Figs. 1 and 2.

The wall 3 of the pocket, which is the front wall when the pocket is in place, is secured to the body just below the slit 2 for the pocket and on the outer face of the shirt, by stitching or otherwise, and a reinforcing tape or strip 8, usually but not necessarily of the same material as the shirt, is secured to the outer face of the shirt bosom, just above the slit, usually by stitching.

After the parts are so connected, as shown in Fig. 4, the pocket is inverted through the slit, as indicated in Fig. 5. The reinforcing tape is then turned through the slit, and both pockets and tape will be on the inner face of the shirt, as shown in Fig. 6.

The wall 4 of the pocket is now secured to the reinforcing tape, as indicated in Fig. 7, thus completing the formation of the pocket.

It will be noticed, particularly referring to Figs. 4, 5 and 6, that the reinforcing tape 8 is formed by doubling a strip of material upon itself. The stitching which connects the strip to the shirt is adjacent to the raw edges of the strip, and when the strip is

turned inwardly through the slit, as shown in Fig. 6, the doubled edge thereof will be upward. To connect the wall 4 to the shirt, the flange, or turned-down portion 6, is hooked over this doubled edge, with the flange between the body of the strip 8 and the shirt bosom, as clearly shown in Fig. 7. The line of stitching indicated at 9 is through the wall, the strip and the flange, 10 as clearly shown in Fig. 7.

Preferably, though not necessarily, the shirt is provided with a flap on the outer face thereof, connected just above the slit and normally hiding the same. This flap 15 may be of an ornamental contour. It is composed of two superimposed pieces 10 and 11, substantially triangular, and secured together, except along the base, by stitching. Thus, a pocket is formed which is inverted 20 before it is applied to the shirt.

The base edge of the flap is secured between the reinforcing tape 8 and the shirt body, and by the same stitching which connects the tape to the body. As shown in 25 Figs. 5 to 11, the edges of the pocket slit are turned inward when the pocket and reinforcing strip are turned through the shirt, providing thus a finish for the slit edges. When the pocket flap is turned down, as 30 shown in Figs. 10 and 11, it hides the pocket slit completely and all of the stitching which connects the flap to the shirt bosom. If desired, the flap may be ornamented, as for instance, by the button 12.

35 The improved pocket and flap construction cooperates with the construction of the closing flap of the above mentioned application to provide a bosom of a very pleasing appearance.

40 In order to provide a neat finish, and to hold the walls of the pocket close up against the shirt front, lines of stitching are provided above and below the slit. These lines are very near the edges of the shirt, the one 45 line passing through the shirt and front

pocket wall, the latter through the shirt front, reinforcing strip, flap, when used, and pocket rear wall.

What I claim is:—

1. The method of attaching pockets to shirts with invisible stitching, which consists in forming a pocket, providing a pocket opening in the shirt, securing a reinforcing tape to the outer face of the shirt above the opening, securing one wall of the pocket to 50 the outer face of the shirt below the opening, inverting the pocket and the reinforce through the opening and securing the other wall of the pocket to the reinforce.

2. The method of attaching a pocket to a 55 shirt with invisible stitching, which consists in securing one wall of a pocket to the outer face of a shirt below a pocket slit, securing a reinforcing tape, or strip, to the outer face of the shirt above the slit, and 60 with a slit covering flap having one edge between the tape and the shirt body, with the flap extending away from the slit, inverting the pocket through the slit, turning in the reinforcing tape, or strip, through the slit, 65 securing the outer wall of the pocket to the strip, and turning down the flap over the slit.

3. The method of attaching pockets to 70 shirts with invisible stitching, which consists in forming a pocket, turning over the free edges of the pocket walls in the same direction on the bodies of the walls, stitching one edge to the outer face of the shirt 75 below the pocket slit, stitching a reinforcing tape, or strip, of the same inaterial to the outer face of the shirt above the pocket slit, inverting the pocket through the slit, turning the reinforce through the slit, and stitching the free edge of the other pocket 80 wall to the reinforce.

Signed at Louisville in the county of Jefferson and State of Kentucky this 5th day of November A. D. 1925.

JOHN H. CRONIN.
